(57) **CLAIM**

The ornamental design for an feeding pump cartridge, as shown and described.

DESCRIPTION

FIG. 1 shows a perspective view of a feeding pump cartridge made in accordance with the design of the present invention; FIG. 2 shows a bottom perspective view of the feeding pump cartridge of FIG. 1;

FIG. 3 shows a top view of the feeding pump cartridge of FIG. 1;

FIG. 4 shows a right side view of the feeding pump cartridge of FIG. 1;

FIG. 5 shows a left side view of the feeding pump cartridge of FIG. 1;

FIG. 6 shows an end view of the feeding pump cartridge of FIG. 1; and,

FIG. 7 shows an opposing end of the feeding pump cartridge of FIG. 1.
